ELECTRON TUBE FOR HIGH FREQUENCY

Gordon T. Howes, Belmont, Calif., assignor to
Eltel-McCullough, Inc., San Bruno, Calif., a
corporation of California

Application February 24, 1945, Serial No. 579,668

9 Claims. (Cl. 250—27.5)

1

My invention relates to a tube having an external anode particularly adapted for high frequency operation.

It is among the broad objects of my invention to provide an improved envelope and terminal structure, and improved means for conductively supporting the electrodes within the envelope.

Another object is to provide an improved concentric stem structure for a cathode.

Another object is to provide a better mounting and terminal structure for a grid.

A further object is to provide an improved cooler for the anode.

The invention possesses other objects and features of advantage, some of which, with the foregoing, will be set forth in the following description of my invention. It is to be understood that I do not limit myself to this disclosure of species of my invention as I may adopt variant embodiments thereof within the scope of the 20 claims.

Referring to the drawings:

Figure 1 is an axial sectional view of a tube embodying the improvements of my invention, this view being about three times actual size, taken in a plane indicated by line 1—1 of Figure 2.

Figure 2 is an end view looking at the grid terminal; and

Figure 3 is a fragmentary sectional view showing a modified grid support.

In terms of broad inclusion, my tube comprises an envelope having an intermediate metallic anode section and vitreous end sections. A cathode stem with inner and outer stem members is arranged at one end of the envelope for supporting the cathode, and a grid terminal member is arranged at the opposite end for supporting the grid. An improved sealing means is provided between the cathode stem members, and an improved structure is provided for mounting the grid on its terminal member. Improvements are also incorporated in the cooler for the anode.

In greater detail, and referring to Figures 1 and 2, my tube comprises an envelope having a tubular metallic anode section 2 with flared ends 3 sealed to envelope sections 4 and 6 of vitreous material such as glass. Section 4 carries an exhaust tubulation which is sealed off at tip 7 after the envelope is evacuated.

A cathode stem is arranged at one end of the envelope comprising an outer tubular metallic stem member 8 and a solid inner metallic stem member 9. These stem members are concentric and both are coaxial with anode 2, the outer member 8 being sealed to vitreous section 4 of

2

the envelope. With a concentric stem arrangement of this kind it is difficult to make a vacuum-tight seal between the members, particularly if outer tube 8 is of small diameter. I have overcome this difficulty by an improved vacuum-tight closure means comprising a metallic sleeve 11 interposed between the stem members, the lower inturned end of the sleeve being sealed to the inner stem rod 9 by a vitreous bead 12 and the upper end being secured to the outer stem tube 8 as by brazing 13 at the rims.

The stem is preferably assembled by first securing sleeve 11 to rod 9 at sealing bead 12, which permits inspection and checking this joint for leaks before placement of these parts in stem tube 8. These parts are then inserted in tubular member 8 and the final joint is made by brazing at 13. Since the braze is at the end of the outer tubular member this joint is also located for easy inspection.

The cathode is preferably of the indirectly heated type comprising a cup-shaped cylindrical body 14 having a suitable emissive surface such as an oxide coating on the cylindrical wall. These 25 oxide coatings are well known, and any of the usual compositions may be used. The lower end of metal body 14 is preferably closed by apertured plate 16, and the body unit is supported on outer stem member 8 by bracket rods 17. The heater for the cathode comprises a resistance coil 18 having its lower end secured to inner stem member 9 and its upper end secured to body 14 by ear 19. This entire cathode and stem structure is inserted into the envelope and sealed in place as a unit.

The grid is of generally tubular or cylindrical construction interposed between the cathode and anode, and preferably comprises longitudinal metal bars 21 secured at one end as by welding or 40 brazing to ring 22 and at the other end to the metal supporting cup 23. This cup is secured to a metallic terminal member 24 by a screw 26. A flange 27 on terminal 24 is sealed to a reentrant portion 28 of envelope section 6. This grid stem structure is coaxial with anode 2 and the concentric cathode stem.

The cooler for dissipating heat from anode 14 comprises a ring-shaped piece 29 having good thermal conductivity, such as copper, with an 45 opening larger in diameter than the external dimension or diameter of envelope portion 6 so that the ring may be slipped over the end of the tube. A core split for the cooler is interposed between the anode and outer ring, comprising a pair 55 of semi-circular copper pieces 31. This three-

piece cooler structure enables it to be assembled about the intermediate anode even though the anode is smaller in diameter than the end portions of the tube. The cooler pieces are preferably secured together and to the anode, as by soldering, to form an integral unit. If desired, fins may be provided on ring 29 for increased radiation.

Figure 3 shows a modified structure adapted for more strenuous operation by providing a more direct and better thermal path for conducting heat away from the grid. This modification also constitutes a simpler and more rigid support for the grid. It comprises an internally extending supporting flange 32 formed integrally with terminal member 28. This one-piece stem structure is preferably of a metal having good thermal conductivity such as copper. The inner end of flange 32 has an annular groove formed between the flange and a lip 33. Grid wires 21 are engaged in this groove and are preferably held by deforming lip 33 inwardly under pressure to solidly grip to wires so that the latter are literally embedded in the copper.

Such a joint is easy to make, has good mechanical strength, and provides an excellent thermal path for heat conduction. If desired, the ends of the grid wires may be otherwise secured as by brazing into the retaining groove, but the compression joint is preferred. A simple way of making the joint is to form lip 33 as an annular outwardly extending flange and then forcing it downwardly and inwardly against the grid wires by a suitable die. In this structure the lower ends of the grid wires are preferably clamped between the faces of a channel-shaped ring 34.

I claim:

1. An electron tube comprising an envelope having a tubular metallic anode section and a vitreous section sealed to an end of the anode section, a tubular metallic stem member sealed to said vitreous section, an inner metallic stem member concentric with said tubular member, vacuum-tight closure means interposed between the stem members, and a cathode within the envelope connected to said stem members.

2. An electron tube comprising an envelope having a tubular metallic anode section and a vitreous section sealed to an end of the anode section, a tubular metallic stem member sealed to said vitreous section, an inner metallic stem member concentric with said tubular member, vacuum-tight closure means interposed between the stem members, a cathode cylinder within the envelope, and a heater within the cylinder connected to said stem members.

3. An electron tube comprising an envelope having a tubular metallic anode section and a vitreous section sealed to an end of the anode section, a tubular metallic stem member sealed to said vitreous section, an inner metallic stem member concentric with said tubular member, vacuum-tight closure means interposed between the stem members, a cathode cylinder within the envelope supported on said tubular stem member, and a heater within the cylinder connected at one end to the inner stem member and at the other end to said cylinder.

4. An electron tube comprising an envelope, a tubular metallic stem member secured to the envelope, an inner metallic stem member concentric with said tubular member, a metallic sleeve interposed between and secured to one of said

members, a vitreous bead sealed to the other end of the sleeve and to said other member, and an electrode in the envelope connected to said stem members.

5. An electron tube comprising an envelope, a tubular metallic stem member secured to the envelope, an inner metallic stem member concentric with said tubular member, a metallic sleeve interposed between the stem members and secured at one end to the tubular member, a vitreous bead sealed to the other end of the sleeve and to said inner member, and an electrode in the envelope connected to said stem members.

6. An electron tube comprising an envelope having a tubular metallic anode section and a vitreous section sealed to an end of the anode section, a tubular metallic stem member sealed to said vitreous section, an inner metallic stem member concentric with said tubular member, a metallic sleeve interposed between and secured to one of said members, a vitreous bead sealed to the other end of the sleeve and to said other member, and an electrode in the envelope connected to said stem members.

7. An electron tube comprising an envelope having a tubular metallic anode section and a vitreous section sealed to each end of the anode section, a tubular metallic stem member sealed to one of said vitreous sections, an inner metallic stem member concentric with said tubular member, vacuum-tight closure means interposed between the stem members, a cathode within the envelope connected to said stem members, a metallic terminal member sealed to the other vitreous envelope section, and a grid in the envelope connected to said terminal member.

8. An electron tube comprising an envelope having a tubular metallic anode section and a vitreous section sealed to each end of the anode section, a tubular metallic stem member sealed to one of said vitreous sections, an inner metallic stem member concentric with said tubular member, vacuum-tight closure means interposed between the stem members, a cathode within the envelope connected to and supported wholly by said stem members, a metallic terminal member sealed to the other vitreous envelope section, and a grid in the envelope connected to and supported wholly by said terminal member.

9. An electron tube comprising an envelope, a tubular metallic stem member secured to the envelope, an inner metallic stem member concentric with said tubular member, vacuum-tight closure means interposed between said members, said closure means including a metallic sleeve projecting into the tubular stem member and secured at one end to said tubular stem member, and an electrode in the envelope connected to said stem members.
